US0D1102824S

(12) **United States Design Patent** (10) **Patent No.:** **US D1,102,824 S**
(45) **Date of Patent:** **** Nov. 25, 2025**

(54) **CUP**

(71) Applicant: **Jingxiang Lin**, Shenzhen (CN)

(72) Inventor: **Jingxiang Lin**, Shenzhen (CN)

(**) Term: **15 Years**

(21) Appl. No.: **29/993,519**

(22) Filed: **Mar. 14, 2025**

(51) **LOC (15) Cl.** **07-01**

(52) **U.S. Cl.**

USPC **D7/509**; D7/624.1

(58) **Field of Classification Search**

USPC D7/509-511, 512, 532, 533, 537, 560,
D7/396.2, 392.1, 396.1, 396.6, 300.2,
D7/624.1; D3/202

CPC A63F 2009/0058; A47G 19/2205; A47J
41/00

(57) **CLAIM**

The ornamental design for a cup, as shown and described.

DESCRIPTION

FIG. 1 is a front perspective view of the first embodiment, showing my new design;

FIG. 2 is a rear perspective view of the first embodiment;

FIG. 3 is a front view of the first embodiment;

FIG. 4 is a rear view of the first embodiment;

FIG. 5 is a left side view of the first embodiment;

FIG. 6 is a right side view of the first embodiment;

FIG. 7 is a top view of the first embodiment;

FIG. 8 is a bottom view of the first embodiment;

FIG. 9 is a front perspective view of the second embodiment;

FIG. 10 is a rear perspective view of the second embodiment;

FIG. 11 is a front view of the second embodiment;

FIG. 12 is a rear view of the second embodiment;

FIG. 13 is a left side view of the second embodiment;

FIG. 14 is a right side view of the second embodiment;

FIG. 15 is a top view of the second embodiment;

FIG. 16 is a bottom view of the second embodiment;

FIG. 17 is a front perspective view showing the cup in a combined state; and,

FIG. 18 is a side perspective view showing the cup in a combined state.

The broken lines in the drawings illustrate the portions of the cup, which form no part of the claimed design.

1 Claim, 18 Drawing Sheets
